US00D361465S

United States Patent [19]Dardashti[11] Patent Number: Des. 361,465[45] Date of Patent:  Aug. 22, 1995[54] TWO-SIDED STORAGE RACK

- [76] Inventor: Shahriar Dardashti, 236 Oakhurst Dr., Beverly Hills, Calif. 90212
- [*] Notice: The portion of the term of this patent subsequent to Jun. 27, 2009 has been disclaimed.
- [] Term: 14 Years
- [21] Appl. No.: 17,108
- [22] Filed: Jan. 5, 1994
- [52] U.S. Cl. D6/630; D6/407
- [58] Field of Search D6/396, 405, 407, 626, D6/629, 630, 462, 467, 468, 477, 478, 479; D19/75, 76, 91, 27, 8; D14/120, 121; 211/40, 41, 42; 206/387; D17/14, 18, 19, 20

Primary Examiner—Alan P. Douglas*Assistant Examiner*—S. Snapp*Attorney, Agent, or Firm*—Poms, Smith, Lande & Rose[57] CLAIM

The ornamental design for a two-sided storage rack, as shown and described.

DESCRIPTION

- FIG. 1 is a front, side perspective view of a two-sided storage rack showing my new design;
 FIG. 2 is a front elevational view thereof;
 FIG. 3 is a rear elevational view thereof;
 FIG. 4 is a left side elevational view thereof;
 FIG. 5 is a right side elevational view thereof;
 FIG. 6 is a top plan view thereof; and,
 FIG. 7 is a bottom plan view thereof.

The broken line showing of the rotatable base is for illustrative purposes only and forms no part of the claimed design.
